UNITED STATES PATENT OFFICE.

ALBERT G. GREEN, OF RED CLOUD, NEBRASKA.

GRAIN CARRIER AND REGULATOR FOR THRASHING-MACHINES.

SPECIFICATION forming part of Letters Patent No. 522,011, dated June 26, 1894.

Application filed March 30, 1894. Serial No. 505,742. (No model.)

To all whom it may concern:

Be it known that I, ALBERT G. GREEN, a citizen of the United States, residing at Red Cloud, in the county of Webster and State of Nebraska, have invented certain new and useful Improvements in Grain Carriers and Regulators for Thrashing-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in feed carriers and regulators for thrashing machines, whereby the grain may be fed to the cylinder, endwise, the bundles cut and the quantity of grain being fed, can be regulated, so that in case of weedy or wet grain, the feeding may be slow, thus preventing clogging of the cylinder.

A further object of the invention is to provide means whereby access can be had readily to the cylinder and concaves, when repairs are necessary, and when it is desired to change the concaves for thrashing different kinds of grain.

To these ends and to such others as the invention may pertain, the same consists in the novel construction, combination and adaptation of the parts as will be hereinafter more fully described and then specifically defined in the appended claims.

I clearly illustrate my invention in the accompanying drawings, which with the letters of reference marked thereon form a part of this specification, and in which similar letters of reference indicate like parts throughout the several views, in which—

Figure 1, is a vertical longitudinal sectional view of my invention. Fig. 2, is a plan view of a portion of the grain carrier. Fig. 3, is an enlarged view of the regulator. Fig. 4 is a detail view of a portion of the interior of the door through which access is had to the cylinder. Fig. 5, is a detail view of one of the arms of the band cutter showing how the knives are made to turn back.

Reference now being had to the details of the drawings by letter, A, represents the main

frame work of a feeding device, which is to be bolted to a thrashing machine.

At B is pivoted the carrier frame C, having the pulleys c c, which carry a series of belt aprons provided with cleats c', and power is communicated to said pulleys from the main driving shaft of the machine. To the free end of the carrier is attached the rope D which passes up over the beam D', then downwardly and around a windlass D², which is provided for raising or lowering the carrier. This rope serves also to prevent the stalks of grain being fed crosswise to the machine, as the stalks fall each side of the said rope and are fed lengthwise to the entrance of the machine. To the end of the carrier is also secured the support E which supports the end of the carrier when feeding loose grain.

Journaled in suitable bearings at F F, is a shaft carrying a series of arms F' with knives F² attached for cutting the bundles of grain. These knives may be closed as illustrated in the drawings, as where loose grain is being fed to the cylinder, and there is no necessity for using the cutters.

To the beam D' is bolted the bracket F' having an aperture G, H being the regulator handle which is connected with a series of regulating tines at h which series of tines is securely attached to the beams I and I', the ends of the latter I', forming pivotal support for the regulator. By means of the bolt h' the regulator may be held in a fixed relation to the carrier, thus regulating the supply of grain being carried to the machine. Secured to a beam J, are the rods J' having their upper free ends curved and adapted to pass between the endless carriers, so as to catch the stalks of grain likely to be carried with the aprons without being carried into the machine. Pivoted at L, L, is a revolving beater L' which is provided to scatter the bundle of grain as it enters, and at M is an equalizer journaled in the side walls of the machine, which throws the grain against the cylinder N.

N' is a series of rods having their free ends interlocking with the arms of the equalizer to prevent the stalks clogging on said arms. The cylinder throws the grain violently against the iron bars of the door O, which is removable, and which when in place assists

in thrashing the grain, making less concave teeth necessary.

The advantages of my invention and the operation of the same will readily be seen, as by this construction, the grain in bundles is fed lengthwise into the machine each side of the cord D, or when loose grain is fed, the rope may be removed. The regulator can be adjusted to regulate the feed, the bundles cut and upon entering, the grain is scattered violently by the revolving box and then the grain coming in contact with the arms of the equalizer, the separated stalks are presented to the cylinder where they are thoroughly thrashed.

15 In case of transportation of the machine, the carrier is folded, it not being necessary to remove the feeder or carrier from the thrashing machine.

Having thus described my invention, what 20 I claim to be new, and desire to secure by Letters Patent, is—

1. In a grain carrier and regulator for thrashing machines, the combination of a series of endless carriers, means as described for presenting the stalks of grain lengthwise to the machine, the curved rods J' or pivoted series of regulating tines, an adjusting lever connected therewith, a band cutter journaled in the sides of the machine frame, the arm prongs

with blades attached which pass between the 30 regulator tines, a square revolving beater journaled within the entrance of the machine, an equalizer for presenting the stalks of grain to the cylinder, and a doffer plate to prevent the clogging of the arms of the equalizer, all sub- 35 substantially as shown and described.

2. In combination with the carrier C, the regulator H, I, knives F² beater L' and equalizer M, as related to a thrashing machine cylinder, of the removable door adjacent to the 40 said cylinder provided with a series of iron rods which are utilized in thrashing grain, substantially as and for the purpose set forth.

3. In combination with the mechanism of a thrashing machine, as described, a cylinder 45 carrying a series of blades which are pivoted within recesses in the ends of suitable holders, and adapted to fold back within a recess of the holders, and a spring for holding the blade in a fixed position, substantially as 50 shown and described.

In testimony whereof I affix my signature in presence of two witnesses.

ALBERT G. GREEN.
